US0D1070752S

(12) **United States Design Patent** (10) **Patent No.:** **US D1,070,752 S**
(45) **Date of Patent:** **** Apr. 15, 2025**

(54) **JUMP STARTER**

(71) Applicant: **Hulkman Innovation Technology (Shenzhen) Co., Ltd.**, Shenzhen (CN)

(72) Inventor: **Yang Wang**, Shenzhen (CN)

(73) Assignee: **HULKMANN INNOVATION TECHNOLOGY (SHENZHEN) CO., LTD.**, Shenzhen (CN)

(**) Term: **15 Years**

(21) Appl. No.: **29/893,458**

(22) Filed: **May 30, 2023**

(51) LOC (15) Cl. **13-02**

(52) U.S. Cl.

USPC **D13/107**

(57) **CLAIM**

The ornamental design for a jump starter as shown and described.

DESCRIPTION

FIG. 1 is a perspective view of a first embodiment of a jump starter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second embodiment of the jump starter;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The broken lines in the Figures are for the purpose of illustrating portions of the jump starter that form no part of the claimed design.

The jump starter is shown with symbolic breaks in its length and the appearance of any portion of the jump starter between the dot-dash lines form no part of the claimed design.

1 Claim, 16 Drawing Sheets
